UNITED STATES PATENT OFFICE.

CARLETON ELLIS, OF MONTCLAIR, NEW JERSEY.

MAKING GASOLENE SUBSTITUTE.

1,396,999.

Specification of Letters Patent.

Patented Nov. 15, 1921.

Application filed October 4, 1913. Serial No. 793,377.

To all whom it may concern:

Be it known that I, CARLETON ELLIS, a citizen of the United States, and a resident of Montclair, in the county of Essex and 5 State of New Jersey, have invented certain new and useful Improvements in Making Gasolene Substitutes, of which the following is a specification.

This invention relates to a process of 10 making gasoline from heavier oils such as kerosene and the like and is related in particular to a system or organization of correlated elements; the whole forming an integral process or organization whereby 15 from heavier oils there may be obtained lighter fractions akin to or suitable for use in place of ordinary gasoline.

In order to render the nature of the organization clear, I have appended two plans 20 showing the path of material undergoing treatment, this being indicated by Figures 1 and 2; while Fig. 3 shows a structure suitable for carrying out the procedure indicated by Fig. 1 and Fig. 4 apparatus for 25 carrying out the procedure indicated by Fig. 2. Fig. 3 is shown mainly in sectional elevation, and, in a diagrammatic manner, shows the heating and condensing system and stabilizing means adapted for carrying 30 out the present system. Fig. 4 shows in a diagrammatic manner a modified form of the apparatus illustrated in Fig. 3 including also additional apparatus hereinafter referred to in the description of the process 35 indicated by Fig. 2. Fig. 5 is a detail sectional view of one of the decomposing tubes showing the manner in which the catalytic material is placed therein.

By referring to Fig. 1 it will be noted 40 that the first member is a decomposer or decomposing tubes. This element may consist of a series of tubes placed in a furnace and adapted to be heated to a temperature of 400-600° C. or so, while the heavier oil 45 passes through in the form of a vapor and is subjected to thermal decomposition during such travel. Of course, the tubes may be long or short according to the velocity of travel of the oil vapors with respect to 50 the temperature of the surrounding gases applied for heating such tubes. Into the decomposer may be admitted along with the oil or oil vapors a quantity of steam so as

to provide 20-50% of water more or less, based on the nature of the oil employed. In 55 place of a tubular structure a retort or still may be employed. In the decomposing tubes I preferably place catalytic material, preferably metal bodies of a shape adapted to form baffling surfaces while permitting 60 a ready flow of the vapor.

Metal which is a good conductor of heat preferably is employed in order by rapid conduction to prevent a cold core of gases along the middle of the tube rendering that 65 part of the tube without effective action. During the first part of the travel of the oil vapors for effective action I preferably bring them into contact with surfaces of copper and in the latter part of the travel 70 with surfaces of nickel. This may be accomplished by plating "jackstones" and the like with copper or respectively with nickel and packing the tubes with the jack stones which pack in such a way that the greatest 75 baffling effect is secured at the center and most rapid travel at the circumference of the tube which, of course, is hottest and therefore an automatic equalization of temperature is secured.

A single passage of the heavy oil through the apparatus should yield an amount of light products adapted for use as a gasoline substitute equivalent to from 20 to 40 per cent. of the original oil treated. After 85 the oil vapors have been decomposed to the required degree, they are passed preferably to a digester which may be and preferably is a vessel well insulated to prevent loss of heat in which container the heated vapors 90 undergo digestion or reaction among themselves and more or less stabilization with establishment of certain conditions of equilibrium which could not be secured satisfactorily in the decomposing tubes where 95 strong heat is being applied externally.

The decomposition products contain unstable constituents which, in the digester, react with the gases present and particularly hydrogen, or with each other or by 100 polymerization, to produce more stable compounds in substantial molecular equilibrium. From the digester the vapors may go to a dephlegmator or fractioning column which preferably is of a type used in the 105 rectification of alcohol and the like in place

of the ordinary coarse dephlegmator used in the present day rectification of oil. In the dephlegmator or fractioning column the heavy oil is condensed and if desired a 5 dephlegmator may be arranged to yield as fractions a gas oil and unconverted kerosene especially if the latter is employed as the raw material. Preferably, however, the kerosene is separated from the heavier oils 10 and the former returned to the decomposing tubes while the latter which is preferably separated as a fraction similar to gas oil, is collected and suitable disposition made thereof. 15 The lighter oils or volatile spirits are not condensed in the dephlegmator and preferably passed into a desulfurator which may be a tube containing copper filings or copper oxid or other metallic or non-metallic 20 desulfuring agent maintained at a temperature suitable for satisfactory desulfurization. Preferably, however, a desulfuring agent similar to that employed in the subsequent process of hydrogenation is made 25 use of.

Oils which have been purified for the market such as, for example, ordinary lamp oil or kerosene contain very little sulfur as a rule, but enough is usually present to 30 affect the catalyst employed in the hydrogenation step which is subsequently to be described, and in that case the sulfur has to be removed in order to secure a catalyst of sufficient endurance. When using a catalyst 35 such as nickel or cobalt, traces of sulfur or chlorin act in a poisonous manner rendering the catalyst in a short time wholly inert. Oils which have been sufficiently desulfurized for commercial purposes often have enough sulfur or other 40 toxic agents to decrease the catalytic activity, because of the great sensitiveness of these catalytic bodies to catalyst poisons. Hence if nickel is employed as a catalyst, 45 preferably the spent nickel catalyst, that is to say the catalyst which has lost its catalytic activity, may be employed for removing those traces of divers bodies which act poisonously. While copper oxid and the 50 like will remove sulfur in a commercially satisfactory way, it is better, as stated, when removing sulfur to fit an oil for catalytic hydrogenation to use as a desulfurizing agent the catalyst itself or spent masses of 55 the same, as thereby the specific selective action of the metal and removal of the particular traces of sulfur or other toxic agents acting on the catalyst is satisfactorily effected, which oftentimes may not be 60 the case when using metals or compounds of dissimilar affinities for the sulfur and other toxic agents.

The product having been suitably prepared in this or other manner for hydrogenation, it is now preferably passed

through a hydrogenating apparatus in which it contacts with nickel or other catalyst in the presence of hydrogen. The nickel is preferably carried on a support of the nature of crushed glass or other dense 70 impermeable material. The glass is preferably fairly uniformly plated with a very thin layer of nickel material. A temperature between 200-300° C. preferably is maintained in the hydrogenator during the 75 operation. The product then passes to a condenser where it may be obtained in a suitable form for the market or, if desired, may be re-distilled or treated with sulfuric acid and alkali or subjected to any other 80 method of treatment, although in general it is sufficient to simply pass the product through the hydrogenator in order to add hydrogen and thereby satisfy the unstable bodies present, as this usually affords a 85 product of good color, odor and stability.

In Fig. 2 the light fraction passes from the dephlegmator uncondensed, the lighter oils and gases being mingled; while according to the plan of Fig. 1, the gas may be 90 removed from the condensed light oils at the dephlegmator. The uncondensed vapors may then pass to a desulfurator and through a temperature regulator where the temperature of the vapors may be adjusted 95 to about 240° C. whereupon they may be introduced into the hydrogenator wherein the free hydrogen contained in the gases of decomposition from the decomposing tubes may be caused to unite with the oil vapors. 100 Hydrogen, of course, may be supplied from an external source in the amount required. The product passes into a condenser and the light oils are thus obtained in a liquid form, while any excess of hydrogen and the 105 other gases which are present containing entrained vapors may be passed to a compressor or scrubber or washer or refrigerator where any useful light oils may be recovered.

A similar operation may be employed in the case of the gas derived according to the system indicated in Fig. 1. These gases may then be passed through a gas decomposer where they are subjected to a very 115 high temperature in order to break down the hydrocarbons into the carbon and hydrogen and after suitable washing or other purification the hydrogen may be returned to the hydrogenator, as described in connection with Fig. 2.

In Fig. 3, 1 is a furnace structure containing a battery of heating tubes as shown at 4, 4^a, 4^b, and 4^c. These consist of pipes set horizontally or practically so, connected 125 end to end in such a manner as to form a continuous passage from the upper horizontal tubes to the lower ones. They are heated by fuel gas supplied through the pipes 2. 3 is a chimney for the spent gases 130

or products of combustion. The tubes 4, 4^a, 4^b, 4^c, may be filled with catalytic and heat-conducting material as shown at 3' (Fig. 5), the uppermost pipes preferably 5 containing copper fragments and the lowermost preferably carrying nickel bodies. A feed-pipe 5 serves for the introduction of oil, oil vapor, oil and water, steam and oil, or the vapors of steam and oil. As shown, a 10 branch pipe 5' may be provided for the introduction of steam or water, the pipe being provided with a suitable valve to permit regulation of the proportions of oil or oil vapor and water or steam. These pass down- 15 wardly through the several series of heating pipes and then by risers 6, 6^a, 6^b, and 6^c, are taken to the manifold 7 which communicates with the digester drum 8. This drum is preferably of considerable length in refer- 20 ence to the diameter and has an inlet for the oil vapors at one end, while the outlet represented in the drawing by 9 preferably is at the other end. The products of combustion from the heaters below the decom- 25 posing tubes pass up and around the drum and in some cases may add heat to it and in other cases may serve more as an insulating blanket of heated air to prevent any substantial drop of temperature in the di- 30 gester 8.

The slow travel of the vapors through the drum enables molecular equilibrium to be established to a considerable degree. The pipe 9 leads to a dephlegmator 10 35 which may be a column apparatus of a type adapted to make fairly sharp separation of close boiling fractions. These may be withdrawn at 11, 11^a and 11^b. A pipe 12 carries the light distillate to a desul- 40 furizer 13 which preferably is filled with spent nickel catalyzer. Gases are with- 45 drawn by the pipe 15 which carries the valve 16. 14 is a trap which enables the gases to be collected at that point. 17 is a pipe lead- 50 ing to the hydrogenator 21. The pipe 17 carries the valve 18. 19 is a pipe serving to introduce hydrogen or other suitable reducing gas, the flow of which therethrough 55 being regulated by the valve 20. A flue 22 conducts gases from the stack 3 to the hy- 60 drogenator 21 in order to furnish heat for the latter, air being admitted to the hy- 65 drogenator by openings, whereby suitable control of temperature is secured which 70 preferably should be between 240-250° C. The hydrogenator as shown consists of a 75 series of tubes 24 connected to form a continuous passage, in the tubes being placed nickel or other catalyzer, but preferably 80 nickel plated or coated on dense imperme- 85 able fragments or granules of such a character as to prevent the vapors from permeating the support. The temperature of the 90 hydrogenator may be regulated by admitting 95 any desired quantity of air in addition to

the products of combustion from the pipe 22. As shown, the casing 21 is provided with openings 21' and shutters or valves 22' are arranged over these openings to permit regulation of the air feed. Thus recovery 70 of the catalyzer when as such it can no longer be used, is made possible, which is difficult when the metal is lodged inside a porous carrier as would be the case with a porous support, causing trouble in re- 75 generation. From the tubes 24, the light oil products are conveyed to a condenser 25 where any remaining condensable fractions are liquefied. The finished product is re- 80 moved from the condenser by outlet 26, and 85 may be delivered to a separator 26' for the purpose of removing any excess water. The material obtained from the outlet 26 or the separator 26' is composed of low boiling saturated hydrocarbons of the nature of 85 gasoline. From the tubes 24 of the hydro- 90 genator 21 the product passes through the condenser 25 provided with the valved out- 95 let 26.

Porous bodies sometimes show a tendency 90 to selectively absorb some portion of the oil, thus tending to clog the catalyzer. Also in the preparation of the catalyzer with a porous support, it is difficult owing to an occlusive force to free such catalyzer from 95 objectionable impurities by washing. Again there is the difficulty of securing a satisfac- 100 tory coating of materials; so for these and for other reasons a carrier of the nature of glass or metal preferably is employed as a support. Thus iron, copper and aluminum and the like may be employed.

In the somewhat modified form of appa- 105 ratus shown in Fig. 4, employed in carrying out the procedure indicated by Fig. 2, a tem- 110 perature regulator 17^a having an inlet 17^b and an outlet 17^c for a suitable temperature regulating fluid is preferably connected in pipe 17 between the desulfurizer 13 and the hydrogenator 21. The temperature of the 115 vapors is preferably adjusted in the tem- 120 perature regulator 17^a to about 240° C. In this form of apparatus the valved outlet 26 from the condenser 25 is connected with a trap 27 where the light oils may be obtained 125 in liquid form and drawn off through the valved outlet 28. The uncondensed gases may advantageously pass through pipe 29 to a scrubber or washer 30 then through the valved connecting pipe 31 to a refrigerator 130 32 then through pipe 33 to a compressor 34 from which the uncondensed portion of the product is returned through valve pipes 35 and 19 to the hydrogenator 21 as herein- 135 above described in connection with Fig. 2, 125 the condensed portion of the product pass- 140 ing from the compressor 34 may be caught in the trap 36 and drawn off through the valve controlled outlet 37.

The desulfurizer may be placed in any 130

one of several locations and may be omitted when the oil is sufficiently free from toxic bodies to have no substantial or objectionable effect on the catalyzer. When water is used in the decomposing tube and an excess is employed this will appear later, on condensation and suitable means should be provided for its removal. The apparatus is preferably run at a slight pressure although a considerable pressure, as several atmospheres may be employed if desired.

The foregoing description of the present system of treatment is not to be construed as a limitation by virtue of any detail herein specified as various deviations therefrom will now be evident to those skilled in this art. For example, various elements may be eliminated under due circumstances, such as the desulfurizer when the oil is at the start sufficiently free from sulfur poisons. Or various elements may be added to the present system, or hydrogenation of the unsaturated components may take place in the liquid state, instead of in the vapor state as specified; the oil then for example being contacted under pressure with finely-divided catalyzer as hydrogen is caused to pass through or contact with the oil while the catalyzer is maintained well intermingled with the oil by any suitable means.

What I claim is:

1. The system of making a gasoline substitute which comprises passing a kerosene or heavier oil through a heated zone wherein decomposition of the oil takes place, in passing the products of decomposition into a digestion chamber and exposing said vapors to digesting conditions, fractionating to remove the heavy fractions, desulfuring the light fractions and hydrogenating same.

2. The system of making gasoline substitute which comprises passing kerosene material through a heated zone in the presence of heat-conducting and catalytic material, in allowing the decomposed material to inter-react to establish equilibrium by digestion, in fractionating same, in collecting the light oil, removing any toxic traces of sulfur present and in hydrogenating the product.

3. The system of making a gasoline substitute which comprises passing kerosene vapors and the like admixed with the vapors of steam through a long passage way heated to a temperature between 400-600° C. and containing first a quantity of metal material comprising copper and second in series a quantity of metal material comprising nickel, in withdrawing the products of decomposition, passing same into and through a digester of great length in order to establish equilibrium in part, in fractionating in collecting the heavy oil as gas oil and kerosene on the one hand and light volatile oil on the other hand, in removing any toxic

traces of sulfur from the light volatile oil, and in combining hydrogen with said light volatile oil.

4. The system of making a gasoline substitute which comprises passing kerosene vapors and the like admixed with the vapors of steam through a long passage way heated to a temperature between 400-600° C. and containing first a quantity of metal material comprising copper and second a quantity of metal material comprising nickel, in withdrawing the products of decomposition and passing these through a digestion conduit of great length, in fractionating, in collecting the heavy oil as gas oil and kerosene on the one hand and light volatile oil on the other hand, in removing any toxic traces of sulfur from the light volatile oil, and in combining hydrogen with said light volatile oil.

5. The system of making a gasoline substitute which comprises passing oils heavier than gasoline through a heat decomposing zone, in digesting the products of decomposition for a protracted period whereby stable saturated bodies are formed, in fractionating to remove the heavier oils, in collecting the uncondensed vapors of light oils and accompanying gases, in passing same through a desulfurizer to remove traces of toxic bodies, in adjusting the temperature to approximately 240-250° C., in passing the vapors and gases through a mass of nickel material in the presence of hydrogen, in condensing the light volatile oil stabilized by hydrogenation, in collecting the gases and removing therefrom the entrained vapors, in combining the very light oils thus secured or any suitable portion thereof with the aforesaid light oils coming from the condensing apparatus, in submitting some portion at least of said gases to a high temperature, whereby decomposition of hydrocarbons takes place, in freeing the hydrogen thereby secured from objectionable impurities and returning same to the zone of hydrogenation.

6. The system of making a gasoline substitute which comprises passing oils heavier than gasoline through a heat decomposing zone, in stabilizing by digesting the products of decomposition, in fractionating to remove the heavier oils, in collecting the uncondensed vapors of light oils and accompanying gases, in passing same through a desulfurizer to remove traces of toxic bodies, in adjusting the temperature to approximately 240-250° C., in passing the vapors and gases through a mass of nickel material in the presence of hydrogen, in condensing the light volatile oil stabilized by hydrogenation, in collecting the gases and removing therefrom the entrained vapors, in combining the very light oils thus secured or any portion thereof with the aforesaid

- light oils coming from the condensing apparatus, in submitting some portion at least of said gases to a high temperature, whereby decomposition of hydrocarbons takes place, 5 in freeing the hydrogen thereby secured from objectionable impurities and returning same to the zone of hydrogenation.
7. The system of making a gasoline substitute which comprises passing oils heavier 10 than gasoline through a heat decomposing zone, in fractionating to remove the heavier oils, in collecting the uncondensed vapors of light oils and accompanying gases, in saturating these in part by digesting causing interaction and formation of more stable products, in passing the vapors and gases through a mass of nickel material in the presence of hydrogen, in condensing the light volatile oil stabilized by hydrogenation, in collecting 15 the gases and removing therefrom the entrained vapors, in combining the very light oils thus secured or any suitable portion thereof with the aforesaid light oils coming from the condensing apparatus, in submitting 20 some portion at least of said gases to a higher temperature, whereby decomposition of hydrocarbons takes place, in freeing the hydrogen thereby secured from objectionable impurities and returning same to 25 the zone of hydrogenation.
8. The process of producing gasoline-like material from heavier oil which consists in heating it to the decomposition temperature of the principal constituents thereof, digesting 30 the resulting decomposition products by holding such products without the substantial loss of heat so that they react upon themselves, and hydrogenating the gasoline-like material produced.
9. The process of producing gasoline-like material from heavier oil which consists in heating it to the decomposition temperature of the principal constituents thereof, digesting 35 the resulting decomposition products by holding such products without the substantial loss of heat so that they react upon themselves, and hydrogenating the gasoline-like material produced.
- 40 9. The process of producing gasoline-like material from heavier oil which consists in heating it to the decomposition temperature of the principal constituents thereof, digesting the resulting decomposition products by 45 holding such products without the substantial loss of heat so that they react upon themselves, and hydrogenating the gasoline-like material produced by subjecting it to the

action of hydrogen in the presence of a catalyst carried by non-porous material, at an 50 elevated temperature.

10. The process of producing gasoline-like material from heavier oil which consists in heating it to the decomposition temperature of the principal constituents thereof, digesting 55 the resulting decomposition products by holding such products without the substantial loss of heat so that they react upon themselves, and hydrogenating the gasoline-like material produced by subjecting it to the 60 action of hydrogen in the presence of nickel plated upon a vitreous support, at an elevated temperature.

11. The process of producing gasoline-like material from heavier oil which consists in 65 heating it to the decomposition temperature of the principal constituents thereof, digesting the resulting decomposition products, by holding such products without the substantial loss of heat so that they react upon 70 themselves, removing catalyst poisons from the gasoline-like material produced and hydrogenating such gasoline-like material.

12. The process of producing gasoline-like material from heavier oil which consists in 75 heating it to the decomposition temperature of the principal constituents thereof, digesting the resulting decomposition products, removing catalyst poisons from the gasoline-like material produced, by the action of 80 spent catalyst and hydrogenating the thus purified product.

13. A stabilized gasoline-like product comprising digested and hydrogenated volatile petroleum material. 85

14. A gasoline-like product comprising digested and hydrogenated decomposition products of petroleum oil.

Signed at Montclair in the county of Essex and State of New Jersey this 2nd day of 90 October, A. D. 1913.
